UNITED STATES PATENT OFFICE.

GEORGE M. KIM, OF PITTSBURGH, PENNSYLVANIA.

CHAIR.

1,300,622.

Specification of Letters Patent. Patented Apr. 15, 1919.

Application filed November 4, 1918. Serial No. 261,086.

To all whom it may concern:

Be it known that I, GEORGE M. KIM, a citizen of the United States, residing at Pittsburgh, in the county of Allegheny and State of Pennsylvania, have invented certain new and useful Improvements in Chairs; and I do hereby declare the following to be a full, clear, and exact description of the invention, such as will enable others skilled in the art to which it appertains to make and use the same.

This invention relates to chairs and more particularly to convertible chairs, and the object of the invention is to provide a chair that may be easily and quickly converted into a lounge or bed, and which is provided with a hinged back adapting it to be used as a bed or as a chair in either a substantially vertical position or in an inclined position to serve as a reclining chair.

The invention will first be hereinafter more particularly described, with reference to the accompanying drawings, which are to be taken as a part of this specification, and then pointed out in the claims at the end of the description.

In said drawings:—

Figure 1 represents a front elevation of my improved chair in normal position;

Fig. 2 is a side elevation of the same indicating in dotted lines the hinged back in an inclined position to serve as a reclining chair;

Fig. 3 is a plan view of the chair converted into a lounge or sleeping couch, or bed;

Fig. 4 is a vertical sectional elevation of the device in the position shown in Fig. 3; and

Fig. 5 is a detail of one of the supporting brackets.

Referring to said drawings, in which the same reference letters are used to denote corresponding parts in different views, the letter A may denote the chair frame consisting of approximately square side frames having arm rests a thereon, one of the said side frames being a counterpart of the other, and the two side frames are connected at the

front and rear by cross-pieces a¹ and a² and provided with a bottom plate a³ and partition a⁴, to form a receptacle a⁵ to receive a pillow or bed clothing, or serve as a wardrobe-box for storing away blankets or clothing. To each side frame is secured, on the rear inner side thereof, a supporting bracket

B, of the form shown more clearly in Fig. 5 of the drawings, one bracket being a counterpart of the other and each consisting of a metal bar having at opposite ends, substantially U-shaped flanges b and b¹ to provide sockets or seats to receive studs or pins c projecting from opposite sides or edges of the chair back C, so as to support said back in substantially an upright position or permit it to be disconnected from the upper socket and turned on the hinge connection with the lower socket to a reclining position or to a substantially horizontal position, to serve either as a reclining chair, or as a lounge or bed, as indicated, respectively in dotted lines in Fig. 2 and in full lines in Fig. 4. Each of said flanges b and b¹ is formed with an upward extension or guard to prevent the studs or pins c from being moved past the flange and out of engagement with said sockets. Said supporting brackets are preferably secured to the inner sides of the side frames of the chair frame in slightly inclined positions, as shown, so as to support the chair back normally in a slightly inclined position. The sockets formed by the flanges b and b¹ are open at the top for the insertion of the studs or pins on the chair-back; but in order to prevent accidental disconnection of the studs with the lower sockets, on which the chair-back hinges, the entrance end of one or both of the sockets b¹ is partially closed by the metal over-hanging the bend in the flange in the plane of the body portion of the bracket, so as to form stops, as at b³, to limit upward movement of the chair-back; said stops however permitting forcible withdrawal of the studs by virtue of the inherent resiliency or laterally yielding capacity of the structure of the chair-frame, when it is desired to remove the chair-back, and to facilitate such removal, the edges of said over-hanging portions may be outwardly beveled, as shown.

D denotes the seat of the chair which is slideable longitudinally to permit the back of the chair to be shifted to the inclined position shown in dotted lines in Fig. 2 of the drawings, or turned down into the position shown in Fig. 4, such movement being accomplished by lifting the back sufficiently to release the upper pins from the sockets on the upper ends of the supporting brackets and lowering the back as desired. In the dotted line position shown in Fig. 2, links

on the free ends of supporting chains E, which are suspended on the inner sides of the side frames A, beside the supporting brackets B, are engaged with the upper pins 5 on the chair-back so as to support said back in an inclined position. The seat D is pivotally supported upon the chair-frame by means of studs or pins d projecting from opposite sides or edges thereof, and entering 10 elongated slots or guide-ways d¹ upon the opposite inner sides of the chair frame, as indicated in dotted lines in Figs. 3 and 4. The said pins d may be formed on metallic plates secured by screws or bolts to the side 15 pieces or edges of the seat frame. In normal position, the seat serves the double purpose of a seat and cover for the underneath receptacle a⁵, and in adjusted position, when slid forward, as indicated in Fig. 4 of the 20 drawings, the seat is slightly inclined to serve as a head-rest, when the device is utilized as a bed or lounge. Both the back and seat may be constructed with side and end pieces secured together in box-like fashion 25 and having a backing of wire fencing material secured to said side and end pieces and suitably covered or upholstered in the usual manner, as indicated more clearly in Fig. 4.

30 I thus provide a very simple, comfortable and inexpensive arm-chair which may be easily converted into a reclining chair or bed or lounge, and which is strong and durable and efficient in practical use. In normal 35 position it is used as an ordinary arm-chair, but may be easily converted into a reclining chair, or into a bed or lounge, by simply lifting the back and securing it in an inclined position, or lowering it to the 40 position shown in Fig. 4, in which position its free end may be supported by suitable legs F, pivoted at one end within the frame of the chair-back, to adapt them to be folded and concealed when not in use.

45 Having thus described my invention, what I claim as new and desire to secure by Letters Patent of the United States, is:—

1. A convertible chair comprising a frame having substantially upright side pieces, a 50 back pivotally supported in a substantially upright position between said side pieces and adapted to swing back into a substantially horizontal position, a seat pivotally supported between said side pieces and adapted to be slid back and forth so as to 55 occupy either a substantially horizontal position, in the upright position of the back, or a slightly inclined position, in the horizontal position of the back, with its rear 60 edge abutting against the lower end of the back in the latter position, adapting the chair to serve as a bed or lounge in the last mentioned positions of the seat and back.

2. A convertible chair comprising a chair- 65 frame having side pieces with arm-rests

thereon, a slideable seat, and a hinged back, said back being hinged intermediate its ends to said chair frame with its lower end arranged to abut against said seat, together with means for supporting said back in either a substantially vertical position, or a rearwardly inclined position, to serve as a reclining chair, or in a substantially horizontal position to serve as a lounge or bed; the seat being adapted to be shifted from a substantially horizontal position, in the vertical position of the back, to a slightly inclined position with its rear edge abutting against the lower end of the back when the latter is lowered to its horizontal position. 70 80

3. In combination, a chair having side pieces with back-supporting brackets secured on the inner rear sides thereof, said brackets each having at each end a substantially U-shaped portion or flange forming a socket 85 with open end to receive studs or pins projecting from opposite sides or edges of the chair-back, whereby said back may be adjusted and supported in either a substantially vertical or slightly inclined position, or thrown back into a substantially horizontal position, together with means for supporting the free end of said back in the last-mentioned position, and means for supporting it in said inclined position. 90 95

4. A convertible arm-chair comprising side pieces or frames suitably connected and braced to provide a chair-frame with arm-rests thereon, a seat slidably fitted between said side pieces, a back hinged to and between said side pieces, and means for supporting said back in either a substantially vertical position, or in a rearwardly inclined position, to serve as a reclining chair, or in a substantially horizontal position, to serve as a bed or lounge. 100 105

5. A convertible arm-chair having side pieces or frames and a seat fitted therebetween, said seat being slideable back and forth into a substantially horizontal or inclined position, and a hinged back, together with means for securing said back in a substantially horizontal position and to hold the seat in a slightly inclined position to serve as a head-rest. 110 115

6. In a convertible chair, a chair-frame having side pieces or frames and a seat slidably fitted therebetween together with an adjustable hinged back, and means for adjusting and securing said back in either a substantially vertical position, or inclined to serve as a reclining chair, or in a substantially horizontal position, to serve as a bed or lounge; said means including supporting brackets on the inner sides of said frames, each having a socket at each end open at its upper end and pins on said back engaging said sockets; the lower sockets and pins serving as hinges on which the back is turned. 120 125 130

7. A convertible chair comprising oppositely disposed upright side pieces or frames, each having secured upon the rear inner side thereof a supporting bracket adapted to hold the chair-back normally in a substantially vertical position, a seat slidably fitted between said frame pieces, and a back hinged therebetween, said back having means thereon engaging said supporting brackets and adapted to be easily disconnected therefrom to permit the back to be moved into a substantially horizontal position, together with means for supporting the free end of said back in the last-mentioned position.
8. In a convertible chair, a supporting

bracket for the chair-back consisting of a metal bar formed at each end with a substantially U-shaped flange offset from the body portion thereof to provide sockets to receive pins projecting from said back, the 20 open end of the socket extending upwardly and one limb of the flange being extended beyond the other to form a guard at the entrance of the socket.

In testimony whereof I affix my signature 25 in the presence of two witnesses.
